UNITED STATES PATENT OFFICE.

GUSTAVOS HEIDEL, OF ST. LOUIS, MISSOURI, ASSIGNOR TO THE NATIONAL SELF HEATING SAD IRON COMPANY, OF SAME PLACE.

SAD-IRON.

SPECIFICATION forming part of Letters Patent No. 414,836, dated November 12, 1889.

Application filed March 17, 1888. Serial No. 267,538. (No model.)

To all whom it may concern:

Be it known that I, GUSTAVOS HEIDEL, of the city of St. Louis, in the State of Missouri, have invented a certain new and useful Improvement in Sad-Irons, of which the following is a full, clear, and exact description, reference being had to the accompanying drawings, forming part of this specification, and in which—

10 Figure I is a side elevation of my improved iron. Fig. II is a rear end view. Fig. III is a vertical longitudinal section through the body, taken on line III III, Fig. II. Part of the tank is also shown in section in this view. 15 Fig. IV is a perspective view showing the parts disconnected.

My present invention relates to certain improvements in self-heating sad-irons.

My invention consists in features of novelty 20 hereinafter fully described, and pointed out in the claims.

Referring to the drawings, 1 represents the body of the iron. This is cast in one piece and is hollow, being composed of a bottom 2, 25 a front 3, sides 4, a top 5 6, (the part 5 of the top being on a higher elevation than the part 6,) and a rear end 7. There is a space from 8 to 9 between the parts 6 and 5 of the top, and the part 6 has a slot or opening 10, extending from a point 11 to the rear end of the iron. The end 7 extends upward but a short 30 distance from the bottom 2, and it preferably has an outwardly-extending flange or lip 12. The top 5 6 of the body is straight and smooth, and upon it rests a plate 13, to which the tank 14, handle 15, and burner 16 are secured. 35 The plate is composed of a flat front portion 17, a flat central portion 18 at a lower elevation than the part 17, and a dome-shaped rear portion 19, the lower edges of which are in line with the bottom of the portion 18, and which, with the portion 18, rest on the part 6 of the top of the body, the arch or dome spanning the slot or opening 10. The forward 40 part of the front portion 17 of the plate rests on the part 5 of the top of the body.

20 represents spaces or openings left between the inner part of the portion 17 of the plate and the part 6 of the top of the body, and between the vertical walls 21 and 22 of the body and plate. Through these openings

20 the heat escapes from the burner after circulating through the body of the iron. (See arrow, Figs. II and III.) The plate is held on the body by ribs or projections 23 thereon 55 at the sides of the dome portion, which engage in rabbets 23^a in the flanges 24 on the part 6 of the top of the body.

In putting the parts together the plate is first placed on the body, as shown by full 60 lines, Fig. IV, and then it is slid forward into the position shown in dotted lines, Fig. IV, which engages the projections 23 with the flanges 24. A thumb-screw 25, which fits and turns loosely in the plate, is then turned and 65 enters a hole 26 in the body, with which it has screw-threaded connection. (See Fig. III.) When it is desired to disconnect the parts, it can easily and quickly be done by simply turning the screw 25 backward until it is disengaged from the hole 26, and then move the plate back to the position shown by full lines, 70 Fig. IV, when it can be lifted off the body.

The burner 16, which may be of any desired construction or form, is connected to the oil-tank 14 by a pipe 27. When the plate is in place on the body, the burner fits within the body, as seen in Fig. III, it entering (as the plate is moved forward in connecting it with the body, as described) the body through the 75 open rear end of the body produced by the part 7, extending but a short distance upward from the bottom 2 of the body. The pipe 27 fits in the opening or slot 10 of the part 6 of the top of the body. The pipe 27 is 80 provided with a valve 28, by which the supply to the burner is regulated.

The tank 14 is connected to the plate 13 by rings 29, through which it is slipped and held from end movement by enlargements 90 30 31 on its respective ends outside of the rings. The enlargement 30 is in the form of a cap that screws onto the tank, (see Fig. III,) and which is applied after the tank is slipped into the rings. The enlargement 31 95 is preferably turned upward and is provided with a valve 32, which may be removed to expose a filling-opening 33, the bottom of which forms the seat of the valve. The valve admits air as the oil is consumed. The rings 100 29 have threaded necks, which screw into threaded sockets 34, formed upon the plate

13, and they are thus removably connected to the plate. They are, of course, screwed into place before the tank is inserted. The supply-pipe 27 has a short portion 27 $\frac{1}{2}$, with right and left threads on its opposite ends. One end screws into the cap or enlargement 30, and the other end into a coupling 36. It is necessary to remove this section of the supply-pipe before the cap 30 can be taken off to allow the tank to be removed from the rings and the rings 29 from the plate 13. The rings 29 have upwardly-extending projections 37, in which is supported a handle 15, preferably of wood. The handle is thus removed a distance from the heat escaping from the body through the openings 20, and the tank is between them.

The entire construction and arrangement produces a cheap, durable, and effective self-heating sad-iron, and one that can be easily and quickly put together and taken apart.

The construction is as applicable to a goose as to an iron, and may be used in either.

The lip 12, together with the cap end of the tank, forms the support for the iron when not in use.

I claim as my invention—

1. A self-heating sad-iron having an integrally-cast hollow body formed with top parts 5 and 6, cast integrally with the body at its ends, said parts 5 and 6 being at different elevations and overhanging the body of the iron, an air-space being left between them, substantially as shown and described.

2. A self-heating sad-iron having an integrally-cast hollow body provided with an upwardly-extended end 7, cast with the body, said end having an outwardly-extended por-

tion, and a plate fitting on the body and carrying a supply-tank and a burner, an opening 40 being formed between the plate and the end 7, substantially as shown and described.

3. In a self-heating sad-iron, a body having a top formed in two parts on different elevations and a plate carrying a burner and supply-tank and having parts on different elevations to fit the top of the body and forming openings 20 between the connecting portions of the parts of different elevations of both body and plate, substantially as and for the purpose set forth.

4. In a self-heating sad-iron, the combination of the body having top parts 5 and 6 at different elevations, a plate having a front portion 17, which rests upon part 5, a depressed middle portion 18, which rests upon the lower part 6, and a rear portion 19, which rises above the depressed portion 18, a tank 14, burner 16, and a handle 15, all combined and operating substantially as and for the purpose set forth.

5. In a self-heating sad-iron, the combination of the body, plate fitting on the body and connected thereto, burner secured to the plate, removable rings connected to the plate, tank fitting in the rings, removable cap 30 on the tank, and supply-pipe 27, connecting the burner to the tank, said pipe having a coupling 36 and a right and left threaded portion 27 $\frac{1}{2}$ screwing into the coupling and into the cap of the tank, substantially as and for the purpose set forth.

GUSTAVOS HEIDEL.

In presence of—

EDWD. S. KNIGHT,

JOS. WAHLE.
